(57) **CLAIM**

The ornamental design for a faucet as shown and described.

DESCRIPTION

FIG. 1 is a perspective view of the faucet;
FIG. 2 is a front view thereof;
FIG. 3 is a rear view thereof;
FIG. 4 is a side view thereof;
FIG. 5 is another side view thereof;
FIG. 6 is a top view thereof; and,
FIG. 7 is a bottom view thereof.

The ornamental design which is claimed is shown in solid lines in the drawings. The broken lines in the drawings are for illustrative purposes only and form no part of the claimed design. Broken lines formed of unequal length dashes (i.e., dash-dot) define bounds of the claimed design.

1 Claim, 5 Drawing Sheets
